[57] CLAIM

The ornamental design for a component hook for aper-
tured boards, substantially as shown.

DESCRIPTION

FIG. 1 is a front side perspective view of the compo-
nent hook for apertured boards showing our new de-
sign;

FIG. 2 is a bottom plan view;

FIG. 3 is an end elevational view taken from the left of
FIG. 1;

FIG. 4 is a rear elevational view;

FIG. 5 is an end elevational view taken from the right of
FIG. 1;

FIG. 6 is a top plan view.
